UNITED STATES PATENT OFFICE.

FRANK MONTROSE, OF CLEVELAND, OHIO.

CHECK-PRINTING MACHINE.

1,384,708.

Specification of Letters Patent. Patented July 12, 1921.

Application filed March 15, 1921. Serial No. 452,469.

To all whom it may concern:

Be it known that I, FRANK MONTROSE, a citizen of the United States, residing at Cleveland, in the county of Cuyahoga and State of Ohio, have invented new and useful Improvements in Check-Printing Machines, of which the following is a specification.

This invention relates to printing or marking devices, particularly to those of the small hand operated type, and has for its object the provision of a device for printing prices upon the checks of waiters in hotels, restaurants, and other places, the device being so constructed and arranged as to print the various amounts upon a strip of paper plain upon one side and carbon-coated upon the other, the carbon-coated side making the imprint upon the check.

An important object is the provision of a device of this character including a rotatable disk carrying the type and movable by means of a handle with which is associated a movable member operating a plunger for forcing a desired type into active position, the disk carrying a series of indicia of progressively varying amounts.

A further object is the provision of a device of this character in which a step by step movement is provided for automatically advancing the strip of carbon paper after each operation of the type member.

An additional object is the provision of a device of this character which will be simple and inexpensive in manufacture, easy to use, a great time and labor saver, and a general improvement in the art.

With the above and other objects and advantages in view, the invention consists in the details of construction to be hereinafter more fully described and claimed and illustrated in the accompanying drawing in which—

Figure 1 is a plan view of my device,
Fig. 2 is a side elevation thereof,

Fig. 3 is a cross sectional view,

Fig. 4 is a cross-sectional view taken on a different plane from that in which Fig. 3 is taken. Fig. 5 is a fragment carried detail perspective view of a movable wheel and Figs. 6, 7 and 8 are detail views of certain portions of the mechanism.

Referring more particularly to the drawings, my device comprises a casing 10 which may be of any desired shape and which is provided at one side with suit-

able slots 11 within which is inserted the check A to be printed and also through which travels a strip 12 of paper which is plain upon one side and carbon-coated upon its other side. This strip of paper is of course initially in roll form with the core 13 of the roller journaled upon a suitable shaft 14. Located at a spaced point is a shaft 15 upon which is a roller 16 upon which the strip is wound subsequent to the printing action to be described, and a step by step movement is provided for moving the strip.

The top of the casing is open or at least formed with a central opening. Mounted within the bottom of the casing is a pedestal 17 forming a bearing within which is journaled an upstanding shaft 18 which carries a disk 19 having its peripheral portion inscribed with progressively increasing amounts ranging from five cents to any desired amount. At its upper end the shaft 18 is provided with a handle 20 by means of which the shaft may be rotated. The top of the casing is formed with a rectangular opening 23 within which any desired one of the bars on the disk is to be brought. The check A to be printed is placed within the slots 11 beneath the strip 12 and is so positioned that the space to be printed will lie beneath the opening 23 in the top of the casing.

Pivottally connected with the peripheral portion of the disk 19 are radial bars 25 which are normally held in elevated position by suitable springs 26 and which carry at their ends type bars 27 which correspond with the indicia on the disk.

Slidable upon the shaft 18 is a washer 28 which is normally pressed upwardly by a coil spring 29 encircling the shaft 18 and bearing against the top of the disk 19. Upon the underside of the handle 20 are ears 30 between which is pivoted a lever 31 which is urged in one direction by a spring 32 and which has one end formed with an elongated slot 33 slidably engaged upon the shaft 18 and engaging the washer 28. Pivottally connected with the washer 28 is a link 34 which has its outer end pivottally connected with an arm 35 which is pivoted with respect to the casing and which is disposed in position to engage which ever type bar 25 is beneath the opening 23.

Associated with the bar 35 is a ratchet

mechanism designated broadly by the numeral 36 and which is for the purpose of advancing the upper strip one step every time the lever 31 is pressed by the operator, that 5 is every time a number is printed.

- In the operation of the device the waiter or cashier places his check within the slots 11 whereupon the cashier grasps the handle and rotates the disk 19 to bring the proper 10 amount indicated thereon into view within the opening 23, this amount indicating the price of the article on the check, as will be understood. The cashier then presses or squeezes the lever 31 toward the handle 20 15 which will result in sliding the washer 28 downwardly upon the shaft 18 and this will cause the link 34 to be moved outwardly, forcing the member 35 downwardly into engagement with the type bar 25 therebeneath 20 corresponding to the amount visible through the opening 23. The type bar thus depressed will engage the paper strip 12 and make an imprint upon the plain side thereof and make a duplicate carbon copy on the check. 25 From the foregoing description and a study of the drawings it will be apparent that I have thus provided a simply constructed and very easily operated check printing device which will be a great time 30 and labor saver and which will avoid mistake as being accurate and making the price quotations on the check proper as the printing is done by the cashier or other similar authorized person. 35 While I have shown and described the preferred embodiment of my invention, it is of course to be understood that I reserve the right to make such changes in the form, construction, and arrangement of parts as will

not depart from the spirit of the invention 40 or the scope of the subjoined claims.

Having thus described my invention I claim:

1. A device of the character described comprising a supporting casing formed with 45 slots, the check to be printed being insertible through said slots, a printing medium passing through said slots above the check, a disk rotatable with respect to the support and having an operating handle, a plurality of 50 radially extending pivoted type bars carried by the disk and adapted to be brought selectively over the proper location upon a check, and a lever operated means for forcing a selected type bar downwardly into engagement 55 with the printing medium.

2. A device of the character described comprising a supporting casing formed with slots, the check to be printed being insertible through said slots, a printing medium passing through said slots above the check, a disk rotatable with respect to the support and having an operating handle, a plurality of 60 radially extending pivoted type bars carried by the disk and adapted to be brought selectively over the proper location upon the check, and a lever operated means for forcing a selected type bar downwardly into engagement with the printing medium, said means comprising a lever pivoted beneath the 65 handle, a washer slidable with respect to the axis of the disk, a link pivotally connected with said washer, and a pivoted member connected with the link and disposed above the place at which the printing is to be accomplished. 70

In testimony whereof I affix my signature.
FRANK MONTROSE.
